UNITED STATES PATENT OFFICE.

JAMES G. WELCH, OF DETROIT, MICHIGAN, ASSIGNOR OF ONE-FOURTH TO JOHN SIN-
CLAIR, ONE-FOURTH TO HARRY JOHN CROSS, AND ONE-FOURTH TO WILLIAM
AITCHISON, ALL OF DETROIT, MICHIGAN.

MAIL-BAG CATCHING AND DELIVERING APPARATUS.

Application filed July 23, 1920. Serial No. 398,361.

To all whom it may concern:

Be it known that I, JAMES G. WELCH, a citizen of the United States, residing at Detroit, in the county of Wayne and State of Michigan, have invented certain new and useful Improvements in Mail-Bag Catching and Delivering Apparatus, of which the following is a specification.

This invention relates to new and useful 10 improvements in mail bag catching and delivering apparatus and more particularly to that type associated with the door of the mail car for delivering and receiving mail bags from a station while the mail car is in 15 progress.

An important object of the invention is to provide a mail bag crane having means associated therewith for securely retaining mail bags and at the same time will permit 20 of their displacement by the proper apparatus at the station.

Another object of the invention is to provide a device of this nature including a mail bag retaining horn associated with the mail 25 train and means for retaining mail bags to be delivered to the station, said retaining horn being connected to the crane and said means in a manner whereby the means may be adjusted to increase or decrease its grip 30 upon the mail bag suspended upon the crane.

Still another object of the invention resides in the provision of an especially constructed crane which may be removably mounted upon the car so that when its use is 35 not desired it may be demounted and placed out of the way.

Other objects and advantages of the invention will become apparent during the course of the following description.

40 In the accompanying drawings forming a part of the application and wherein like numerals are employed to designate like parts throughout the several views

Figure 1 is a side elevation of a mail car 45 with the invention applied thereto.

Figure 2 is a fragmentary horizontal section taken on the line 2—2 of Figure 1.

Figure 3 is a vertical transverse section taken through the car at the doorway there- 50 of illustrating the crane in an extended position, and

Figure 4 is an enlarged fragmentary longitudinal section through the receiving end of the crane.

Referring to the drawings wherein for the purpose of illustration is shown the preferred embodiment of my invention, the numeral 1 designates a railway car having the usual door way 2 therein and to one side 3 of which is secured a pair of spaced brackets 4 having vertically disposed openings or bearings provided therein. The openings in the two brackets are aligned to receive the angularly arranged downwardly directed free ends 5 of a pair of spaced horizontally arranged arms 6 constituting parts of the mail bag crane indicated in its entirety by the numeral 7. As most clearly seen in Figure 3 of the drawing, the two arms 6 are of substantial length whereby they will extend a distance laterally of the side of the mail car when the crane is swung to an extended position. The outer ends of these arms are directed vertically as at 8 to meet at a point substantially between the horizontal portions of the arms 6 from which point the arms are secured together and extended further in parallelism with the arms to provide for the mail bag receiving portion 9 of the crane. The outer end 10 of the mail bag receiving portion 9 is angularly disposed in a horizontal plane to extend forwardly in the direction in which the car is moving.

In order to prevent accidental displacement of the crane from the car and to retain the same in an extended position to perform its functions, a member 11 in the form of a relatively heavy bar is secured to the outside of the car adjacent the side of the door way upon which the crane 7 is mounted. The edge of the member 11 adjacent the door way is provided with a pair of spaced notches 12 to form seats for receiving therein portions of the arms 6 of the mail bag crane 7 when the latter is arranged in an extended position. Consequently it will be seen that wear normally imposed upon the side of the door way by the abutment therewith of the crane 7 is taken up by the plate 11, and that the free ends 5 of the arms 6 of the crane are prevented from accidental displacement from their brackets 4 inasmuch as such movement as will cause the same to become displaced from its bracket, is prohibited by the arms 6 abutting with the relative upper sides of the notches 12. In order to prevent the crane from swinging inwardly

through the door way 2, when such movement is not desired, a latch 13 constituting a plate pivoted between its ends to the notched edge of the member 11 is provided. 5 This latch is pivoted above the uppermost arms 6 of the crane and in a position whereby one end of the latch may swing across the uppermost notch 12 to retain therein one arm 6 of the crane.

10 I contemplate the use of rings 14 in connection with mail bags or sacks of any desired construction, and these bags are suspended from the angular end 10 of the crane by the rings thereof being received 15 and retained between the bottom of the angular end 10 and the free end of a flat spring 16. It will be noted that the free end of this spring is extended beyond the outwardly extending portion 9 of the crane 20 while its opposite end is secured by a bolt 17 or other suitable means to the nose or free end of the angular portion of the crane. As it is desirable to prevent accidental displacement of the mail bags during 25 movement of the mail car due to swaying thereof, I have provided a means for adjusting the tension of the spring 16 whereby the rings 14 carried by the mail bag may be more firmly gripped between this spring and 30 the angular free end 10 of the crane. This means consists of a retaining horn 18 which is arranged in spaced relation above the top of the end 10 of the frame and opens adjacent the portion 9 of the crane to prevent 35 accidental displacement of mail bags delivered to the crane from the station. The horn 18 is provided with an angularly threaded shank 19 which is threaded vertically through the free end of the crane and this 40 threaded shank also extends through an opening in the spring 16. A nut 20 is threaded upon the lower end of the crank 19 to prevent accidental displacement of the horn from the crane. Obviously then it will 45 be seen that upon turning movement of the horn 18 to space it further from the top of the portion 10 of the crane, the shank of the horn will be moved through the crane to cause depression of the spring 17 adjacent 50 its fastening element 17 whereby the spring may be arranged in close proximity to the crane, thereby effecting the tension of the spring.

It is to be understood that this crane may 55 be used upon either side of the mail car and that any kind of suitable station delivering and receiving means may be provided for interchanging the mail bags with the crane

carried by the mail car. However, in the present instance I have illustrated a station 60 delivering apparatus designated in its entirety by the numeral 21 consisting of a vertically supported post 22 having a pair of arms 23 and 24 secured thereto and extending in opposite directions. It will be apparent that this station apparatus is similar 65 to that disclosed in my co-pending application S. N. 306,314 and that these arms are arranged in different horizontal planes and spaced from the post 22 whereby the free 70 end of the crane 7 may pass therebetween and exchange mail bags therewith. The free end of the arm 24 is provided with a flat spring 25 whereby the ring 14 of a mail pouch may be received between this spring 75 and the free ends of the arm and may be readily disengaged from therebetween by the free end of the crane passing through the ring 14 of the bag. The other arm 23 is provided upon its top and bottom with 80 a pair of bowed members 26 and 27 providing means for disengaging the ring of the mail bag from between the spring 16 and the free end of the crane 7 and also providing a pair of shoulders 28 and 29 which 85 prevent accidental displacement of the mail bag with the arms 23 after it has been received thereon from the apparatus carried by the frame.

The foregoing description and the accompanying drawings have reference to the preferred embodiment of my invention. It is to be understood however that such changes may be made in construction and combination of parts, materials, dimensions, etc., as may prove expedient and fall within the scope of the appended claim.

Having thus fully described my invention what I claim as new and desire to secure by Letters Patent is:—

100 A mail bag crane comprising a pair of horizontally disposed spaced arms, said arms being bent between their ends to extend and meet each other, the contacting portions of said arms being secured together and directed parallel to and in the same plane with said arms, and the terminals of the contacting portions being extended at right angles to the plane of the arms and provided with mail bag catching means. 105

110 In testimony whereof I affix my signature in presence of two witnesses.

JAMES G. WELCH.
